Josef Gründl

UNITED STATES PATENT OFFICE.

JOSEF GRÜNDEL, OF NEW YORK, N. Y.

LADDER.

Application filed August 2, 1922. Serial No. 579,284.

To all whom it may concern:

Be it known that I, JOSEF GRÜNDEL, a citizen of Germany, and resident of the city of New York, in the county of New York and State of New York, have invented certain new and useful Improvements in Ladders, of which the following is a specification.

The present invention relates to ladders and more particularly of the class known as "knockdown" ladders.

The main object of the invention is to provide a ladder, the rungs and stiles of which may be conveniently separated and the ladder taken apart and readily reassembled without the use of additional fastening means, each stile being made of a plurality of separable sections, none of which extends a greater distance than from one rung to another.

Another object of the invention is to provide a ladder of the type mentioned which is simple in construction, efficient in operation, durable in use and capable of manufacture on a commercial scale, or in other words one which is not so difficult to make as to be beyond the reasonable cost of such a contrivance.

With these and other objects in view, which will more fully appear as the nature of the invention is better understood, the same consists in the combination, arrangement and construction of parts hereinafter described, pointed out in the appended claim and illustrated in the accompanying drawings, it being understood that many changes may be made in the size and proportion of the several parts and details of construction, within the scope of the appended claim, without departing from the spirit or sacrificing any of the advantages of the invention.

One of the many possible embodiments of the invention is illustrated in the accompanying drawings, in which:—

Figure 1 is a side elevation of two sections of one stile of a ladder, constructed in accordance with the present invention; Fig. 2 is a front elevation thereof; and Fig.

3 is a section taken on line 3—3 of Fig. 1.

Each of the stiles of the ladder is composed of a plurality of sections 10, all of which are alike in construction. Each stile section is joined with the next in the series by groove and tongue joints, separation of

the sections being prevented, as will herein-after appear, by the rungs 11. Each stile section is provided in its upper horizontal edge with a tongue 12 and in its lower horizontal edge with a tongue 13, the tongue 12 extending horizontally from the longitudinal edge 14 of the section and the tongue 13 from the opposite longitudinal edge, denoted by the numeral 15, the tongues running horizontally and extending each through a distance which corresponds, preferably, to one-third of the width of the stile section. From the upper horizontal edge downwards a longitudinal portion of the stile section is removed along the edge 15 thereof, as indicated at 16, there being an oblong mortise 17 formed in the structure remaining a substantial distance below the upper horizontal edge of the stile section. A horizontal groove 18 is formed above the lower edge of the mortise in alignment with the tongue 13, said groove extending from the longitudinal edge 15 of the stile section toward the edge 14 and communicating with the bottom of the mortise 17 and being of a size adapted to receive the tongue 13 of the next section in the series. Similarly, there is removed from the lower horizontal edge upwards a longitudinal portion of the stile section along the longitudinal edge 14 thereof, as indicated at 19, there being an oblong mortise 20 formed in the structure remaining a substantial distance above the lower horizontal edge of the stile section. A horizontal groove 21 is cut below the upper edge of the mortise 20 in alignment with the tongue 12, said groove extending from the longitudinal edge 14 of the stile section toward the edge 15 and communicating with the top of said mortise, and being of a size adapted to receive the tongue 12 of the next section in the series. The portions 10' of each section between the tongues 12, 13 and cut out edges 16 and 19 respectively, form tenons which engage respectively in the top and bottom portions of the mortises 20 and 17. Tenon and mortise joints alined with the tongue and groove joints being thus provided when the parts are assembled.

In assembling two sections of a stile, the upper portion of one is placed into the recess 20 of the other, whereby the tongue 12 of the former is brought into registering position with the groove 21 of the other, and the tongue 13 of the second-mentioned sec-

tion is brought into alignment with the groove 18 of the first-mentioned section. One section is then shifted longitudinally in relation to the other, whereby the corresponding grooves and tongues are interlocked. When the elements are in these positions, they cannot move laterally in relation to one another by reason of the fact that the tongues 12 and 13 do not extend throughout the widths of the stile sections. It is also to be noted that when the elements are thus assembled, the mortises in the adjoining ends thereof form an oblong slot 22. When the end of a rung 11 is inserted into this slot, it prevents longitudinal movement of the stile sections in relation to one another, holding thus the stile sections in operative relation without the use of additional fastening means. From this it appears that the rungs act as wedges, forcing the stile sections longitudinally in opposite directions.

What I claim is:—

A knockdown ladder comprising stiles, each made of a plurality of sections, the meeting ends of adjoining sections being provided with tongue and groove joints extending only through part of the width of said sections, said joints being disposed on opposite edges of the stile and spaced longitudinally thereof, said meeting ends being further provided intermediate said tongue and groove joints with aligned tenon and mortise joints, the opposed ends of the tenons on the two sections being spaced to provide a slot, and a rung end inserted into said slot serving for directly connecting the sections of the stile and preventing their longitudinal movement in relation to one another.

Signed at New York, in the county of New York and State of New York, this 22nd day of June, A. D. 1922.

JOSEF GRÜNDL
